UNITED STATES PATENT OFFICE.

WILLIS H. COLBY, OF DETROIT, MICHIGAN.

DESIGN FOR A COMBINATION INKWELL, CALENDAR, AND DESK RACK.

61,386.

Specification for Design.

Patented Aug. 22, 1922.

Application filed May 9, 1922. Serial No. 2,153. Term of patent 14 years.

To all whom it may concern:

Be it known that I, WILLIS H. COLBY, a citizen of the United States, residing at Detroit, in the county of Wayne and State of Michigan, have invented a new, original, and ornamental Design for a Combination Inkwell, Calendar, and Desk Rack, of which the following is a specification, reference being had to the accompanying drawing, forming part thereof.

I claim:

The ornamental design for a combination inkwell, calendar, and desk rack, as shown.

WILLIS H. COLBY.
